7 Claims. (Cl. 209—172.5)

1

This invention relates to apparatus for separating solid materials and has more particular reference to apparatus for separating solid materials of different specific gravities by means of a suspension.

One object of the present invention is to provide novel and improved apparatus for separating solid materials of different specific gravities by means of a suspension, as for example, in coal washing installations, for separating slate, sand or other heavy constituents from the coal.

Another object of the present invention is to provide apparatus, as characterized above, including a sedimentation vat into and through which the dense liquid flows, an inclined annular casing positioned at one side of the vat with the lower end of the casing forming the bottom portion of the vat to receive the heavy settled solids, and lifting means mounted in the inclined casing for raising the solid material up to an evacuation duct formed in the upper portion of the casing so that the solid material will be evacuated therethrough.

Another object of the invention is to provide apparatus, as characterized above, wherein the mechanical parts are so constructed as to minimize the abrasive action of the dense liquid.

Another object of the present invention is to provide apparatus, as characterized above, in which the lifting means comprises a paddle wheel, the bearings and control mechanism of which are protected from the dense liquid without the necessity of using sealing joints.

Another object of the invention is to provide apparatus, as characterized above, in which the paddle wheel blades are provided with means to eliminate friction caused by the solid material as it is raised by the wheel and to prevent pieces of metal scrap from becoming wedged between the paddle wheel and the casing.

Another object of the invention is to provide apparatus, as characterized above, in which means are provided to prevent the crushing of large pieces of light material as they are evacuated over the overflow sill of the vat.

Another object of the invention is to provide apparatus, as characterized above, in which means are provided to automatically adjust the specific gravity of the dense liquid at the overflow sill of the vat, whereby control may be had over the sinking of the heavy products.

A further object of the invention is to provide apparatus for separating solid material of different densities by means of a suspension, which is simple and inexpensive in construction and rugged and efficient in operation.

Other objects and advantages of the invention will appear in the following specification when considered with the accompanying drawings, wherein:

Fig. 1 is a vertical, transverse section of one embodiment of apparatus constructed in accordance with the present invention;

Fig. 2 is a sectional view taken on the line 2—2 of Fig. 1, looking to the right;

Fig. 3 is a sectional view taken on the line 2—2 of Fig. 1, looking to the left;

Fig. 4 is a fragmentary plan view of the apparatus shown in Figs. 1 and 2;

Fig. 5 is a longitudinal sectional view of the vat in Fig. 1, and showing apparatus for controlling the specific gravity of the liquid in the vat;

Fig. 6 is a fragmentary, transverse sectional view of the apparatus shown in Fig. 1, but showing a modified form of paddle wheel;

Fig. 7 is a view similar to Fig. 6, but showing another modified form of paddle wheel; and

Fig. 8 is a view similar to that shown in Fig. 2, but showing a travelling conveyor belt substituted for the paddle wheel for removing the lighter solids.

In accordance with this invention, dense liquid and solid substances of different specific gravities are delivered to a large tank or vat wherein a liquid level is maintained and the heavy products fall to the bottom; while the lighter products are evacuated by overflowing with the liquid. The dense liquid may be a suspension, for example, a mixture of fine sand and water. The heavy products, which settle to the bottom, are removed from the tank by means of a rotating paddle wheel or conveyor mounted in an inclined annular casing arranged at one side of the tank. The invention also provides means for compensating for differences in specific gravity of the dense liquid at the overflow by feeding the dense liquid at different angles into the main tank.

One embodiment of the invention is shown in Figs. 1, 2 and 3, wherein the dense liquid and the solid material to be separated are delivered into a generally rectangular sedimentation tank 10 having vertical side walls 11 and 12. The tank is shown as having a rounded bottom 13 which merges into the bottom portion of an annular casing 14 into which the heavy products fall to be evacuated from the tank. At one end of the tank the dense liquid is shown as being delivered through one or more conduits 15 provided with wide nozzles 16 between upper and lower inclined plates 17 and 18. The upper plate 17 provides an inclined chute for introducing the solid material to be separated.

The floating products are discharged from the tank 10 over an outlet sill 19 at the end opposite from the inlet conduit. The floating, lighter products are adapted to be evacuated by a transverse paddle wheel 20 mounted on a shaft 21 and driven by a belt 22 operated by a motor 23.

Referring to Fig. 1, the heavy products which

fall into the bottom of the tank and in the bottom portion of the annular casing 14, are adapted to be evacuated from the tank by means of a rotating paddle wheel 24 mounted on a conical hub member 25 and driven by a shaft 26 having a bearing 27 at the upper end of a conical housing 28 connected at its lower end to the bottom wall of the annular casing 14. This arrangement is such that the bearing is above the level of the dense liquid in the tank and is not subjected to wear by granular products to be separated therefrom. Also, the arrangement avoids the necessity of using specially packed, water-tight bearings. The shaft 26 is adapted to be driven by any suitable power means. In this example, it is shown as having a worm wheel 29 driven by a worm 30 on a shaft 31 carrying a pulley 32 adapted to be connected by a belt 33 to a pulley 34, also operated by the motor 23.

As clearly shown in Figs. 1 and 2, the paddle wheel 24 has radial blades 35 which are adapted to contact the bottom and outer walls of the annular casing and convey the separated heavy products from the bottom portion of the tank to an outlet opening 36 in the upper portion of the annular casing, above the level of the liquid in the tank 10. Then, the separated products are discharged through an outlet conduit or chute 37. The blades are shown as being perforated to permit the water to flow back into the tank as the material is being discharged. Also, each blade is shown as having a pair of generally rectangular reinforcing cleats 38 on its rear face, with the widest part of the cleats at the inner end of the blade. The cleated blades are radially removably mounted on the hub member 25 between bracket members 39.

A drain nipple 40 is shown as being connected to the lower part of the annular casing 14 to permit the bottom of the tank and the casing to be cleaned out periodically. It is shown as being closed by a closure cover 41.

In Fig. 5, there is shown one embodiment of means to control the specific gravity of unstable dense liquid in the vat, so that heavier or lighter solids may be recovered at the outlet sill. This may be accomplished in various ways by measuring the density of the dense liquid at a given point in the vat near the level of the outlet sill and adjusting the angularity of the entering stream of dense liquid to change the density of the liquid in the vat.

In the illustrated example, a continuous stream or flow of the dense liquid is removed from the vat just below the level of the sill through a sampling conduit 42 to a float chamber 43 having an open upper end and a restricted outlet opening at its lower end, as shown, so that it will always be filled with liquid and the excess liquid will spill over the top of it.

The overflow chamber 43 is mounted within and overflows into a large container 44 which is closed at its upper end by a cover plate 45 and has a large outlet 46 at the bottom to permit all of the overflowing liquid to drain out through a conduit 47 for subsequent re-use in the vat.

A sensitive float 48 having a vertical stem 49 is submerged in the trapped liquid in the chamber 43. The stem 49 is guided by a pair of vertically spaced spider bearings 50 and 51 across the chamber 43 and container 44. The upper end portion of the float stem carries a switch operating element 52 coacting with spaced switch elements 53-54 of a relay 55 connected by conductors 56-57 to a reversible servo-motor 58.

The servo-motor 58 is connected by a chain belt 59 to a pulley 60 which operates a crank arm 61 pivotally connected to one end of a link 62. The link is pivotally connected at its other end to a crank arm 63 rigidly connected to a pivotally mounted baffle or lip 64 extending below and across the mouth of the nozzle 16 to direct the stream of entering dense liquid into the vat at angles responsive to changes in the position of the float 48. The arrangement is such that changes in the position of the float will close the circuit to the servo-motor and will maintain the specific gravity of the dense liquid in the vat substantially constant, at the overflow sill. The curved dotted lines in Fig. 5 show two angular directions of flow of the dense liquid longitudinally of the vat. The vectors *s*, *g* and *r* represent the direction of flow of the stream of dense liquid, the direction of gravity and the resultant, respectively. The direction of the resultant *r* directly controls the specific gravity of the dense liquid at the overflow sill. The higher the angle of the stream, the greater will be the specific gravity of the dense liquid at the overflow sill.

25 In Fig. 6 there is shown a modification of the separator, especially adapted for use in separating solid matter which may contain scraps of metal, such as bolts and the like, which would otherwise choke up the paddle wheel conveyor.

30 In this modification, the annular casing 14 extends slightly beyond and below the bottom portion of the tank 10 and each of the paddle wheel blades carries arc-shaped angle irons 65 secured to their bottom and end edges to provide peripheral crowns on which the solid matter to be separated is caught and conveyed by the rotating blades to an outlet conduit 66 which communicates with the annular casing adjacent to the inner end of the blades just above the level of the liquid in the tank. This arrangement permits the blades to carry off all the solid matter and discharge it downwardly into the outlet conduit.

In Fig. 7 there is shown another modified construction of the tank and the paddle wheel casing. In that example, the paddle wheel is in the form of an annular cup 67 which is rectangular in cross section and divided into compartments by perforated radial plates 68 and these compartments are open at their inner ends to spill the solid matter in the outlet conduit 69.

In Fig. 8 there is shown a modification of the arrangement for evacuating the material from the top of the tank over the outlet sill. In that modification, there is shown an endless flexible belt 70 trained over wide pulleys 71 and 72 and having integral fins or blade members 73 riding on the sill and arranged to convey the separated, light material over the outlet sill of the tank.

60 Otherwise, the construction may be similar to that shown in any of the other modifications. This arrangement is desirable for handling large lumps of separated material which would choke up a paddle wheel.

65 From the foregoing description, the operation of the separator will be clear to those skilled in the art. It is relatively simple in construction and will last much longer than ordinary separators wherein the bearings for rotating the conveyors are submerged and are exposed to wear or abrasion due to the particles in the liquid.

Obviously, the invention is not restricted to the particular embodiment thereof herein shown and described, but is capable of various modifications within the scope of the appended claims.

What is claimed is:

1. In an apparatus for separating solid materials having different specific gravities, comprising an elongated sedimentation tank for holding a body of dense liquid, said tank having an overflow sill along one end, a chute for introducing the material to be separated into the tank, and means for introducing dense liquid into said tank to create a stream of dense liquid flowing toward said overflow sill, whereby the lighter separated material will be evacuated over the overflow sill; an inclined open-top annular casing positioned at one side of said tank with its lower end opening into and forming the bottom portion of the tank to receive the heavy settled material, said casing having an outlet opening in its upper end portion above the liquid level in the tank, the side wall of the tank adjacent the annular casing acting as a baffle member preventing the flow of the lighter material from the tank into the casing; a hollow shaft housing extending upwardly from said casing to a point above the normal liquid level therein; a shaft rotatably mounted in said housing and extending in a direction perpendicular to the bottom of said casing with its upper end extending through the upper end portion of said housing; a paddle wheel including a hub connected to the upper end of said shaft and carrying a plurality of circumferentially spaced radially extending blades rotatably mounted in said casing; and power means for rotating said shaft and said wheel for raising the heavy material settled in the bottom of the tank up to the outlet opening in the casing for evacuation therethrough.

2. Apparatus as set forth in claim 1, wherein said paddle wheel is in the form of an annular cup, generally rectangular in cross section and wherein said circumferentially spaced and radially extending blades are perforated plates which divide said annular cup into radial compartments, said compartments being open at their inner ends.

3. Apparatus as set forth in claim 1, wherein each of the paddle wheel blades carries an arc-shaped angle iron secured to its bottom and end edges to provide a peripheral crown on which the settled solid material is caught and conveyed by the rotating blades to the outlet opening in the upper portion of the casing.

4. Apparatus as set forth in claim 1, wherein the lower portion of the annular casing extends slightly beyond and below the outer side wall of said tank.

5. In apparatus for separating solid materials

having different specific gravities by suspension, comprising a tank for holding a body of dense liquid, said tank having an overflow sill along one end; a chute for introducing the material to be separated into the tank; and means for introducing dense liquid in the form of a suspension into said tank to create a stream of dense liquid flowing toward said overflow sill; a specific gravity measuring device for measuring the density of the dense liquid at the overflow sill; and means including a motor actuated by said specific gravity measuring device for varying the angular direction of flow of the stream of dense liquid across the tank in response to changes in the measured density of the dense liquid.

10 6. Apparatus, as set forth in claim 5, wherein said specific gravity measuring device includes a float chamber open at its upper end and having a restricted opening in its bottom end, a conduit connected to said chamber and to said tank at a point adjacent to the overflow sill to permit a continuous flow of dense liquid from said tank to said chamber to always keep it filled; and a sensitive float having an elongated stem mounted in said chamber.

20 7. Apparatus, as set forth in claim 5, wherein said means for introducing dense liquid into said tank comprises at least one conduit having a wide nozzle and wherein said means for varying the angular direction of flow of the stream of dense liquid across the tank includes a transverse baffle member pivotally mounted below said nozzle to deflect the stream of dense liquid as it emerges therefrom; a reversible servo-motor operable in response to variations in the measured density of the dense liquid at the overflow sill connected to move the baffle member about its pivotal axis.
